(57) **CLAIM**

The ornamental design for a vehicle mirror, as shown and described.

DESCRIPTION

FIG. 1 is a left side elevational view of a left vehicle mirror (the right vehicle mirror being a mirror image and is not shown);

FIG. 2 is a right side elevational view of the vehicle mirror;

FIG. 3 is a front elevational view of the vehicle mirror;

FIG. 4 is a rear elevational view of the vehicle mirror;

FIG. 5 is a top plan view of the vehicle mirror;

FIG. 6 is a bottom plan view of the vehicle mirror;

FIG. 7 is a perspective view of the vehicle mirror; and,

FIG. 8 is another perspective view of the vehicle mirror.
